EXPANSIBLE BRACELET

Kurt Speck, Palisades Park, N. J., assignor to
F. & V. Manufacturing Co., Inc., East Providence,
R. I., a corporation of Rhode Island

Application April 16, 1948, Serial No. 145,757

Term of patent 3½ years

(Cl. D45—4)

To all whom it may concern:

Be it known that I, Kurt Speck, a citizen of the United States, residing at 529 Lawn Avenue, Palisades Park, in the county of Bergen and State of New Jersey, have invented a new, original, and ornamental Design for an Expansible Bracelet, of which the following is a specification, reference being had to the accompanying drawing, forming part thereof.

Fig. 1 is a front view of an expansible bracelet showing my new design;

Fig. 2 is an edge view of the same; and
Fig. 3 is a rear view of the same.

Fig. 4 is an enlarged perspective view of one of the top links.

I claim:

The ornamental design for an expansible bracelet, as shown.

KURT SPECK.
